UNITED STATES PATENT OFFICE.

WILLIAM A. SMITH, OF DETROIT, MICHIGAN, ASSIGNOR TO CHICAGO PNEUMATIC TOOL COMPANY, OF NEW YORK, N. Y., A CORPORATION OF NEW JERSEY.

COMBINED THROTTLE AND GOVERNOR FOR PNEUMATIC TOOLS.

Application filed July 25, 1921. Serial No. 487,375.

To all whom it may concern:

Be it known that I, WILLIAM A. SMITH, a citizen of the United States of America, residing at Detroit, in the county of Wayne 5 and State of Michigan, have invented certain new and useful Improvements in Combined Throttles and Governors for Pneumatic Tools, of which the following is a specification, reference being had therein to 10 the accompanying drawings.

The invention relates to pneumatic tools of that type in which a reciprocating percussive mechanism is combined with a separate motor for rotating the tool and the invention 15 consists in the means for automatically governing the rotary motor and in the peculiar construction and arrangement of parts as hereinafter set forth.

In the drawings:

20 Figure 1 is a central longitudinal section through the tool;

Figure 2 is a fragmentary sectional view taken in a different plane;

25 Figure 3 is a cross-section on line 3-3 of Figure 1;

Figure 4 is a cross-section in the plane of the throttle valve on line 4-4 of Figure 1;

30 Figure 5 is a similar view showing the ports and passages diagrammatically;

Figure 6 is a section through the ball valve on the line 6-6 of Figure 5.

Heretofore constructions have been devised in which an automatic valve is located 35 in the conduit between the throttle and the motor and is actuated by back pressure from the motor to vary the opening. With the present invention the governing valve is located directly within the throttle, thereby 40 simplifying the construction.

In detail, A is a barrel or cylinder of a percussive motor of any suitable construction, containing the reciprocating piston B. C is the anvil for receiving the impact of

45 the piston, D the tool and E a revolvable sleeve or tool holder which is driven by a peripheral gear F intermeshing with the pinion G on a shaft H revolved by the rotary motor I, preferably of the gear type 50 through the medium of the motor shaft I' and the reduction gears I² and I³ (Fig. 3).

The compressed air or other motive fluid, while operating both the percussive motor and the rotary motor, is supplied through 55 a connection J, and K is a throttle valve

for controlling the supply. The valve K is preferably of the hollow plug type having one end in communication with the fluid supply and being also provided with ports L and M for registration respectively with 60 passages O and P leading to the reciprocatory and rotary motors. Thus by rotating the plug through the medium of a suitable handle, the fluid is turned on or off simultaneously with respect to both motors. 65

For governing the rotary motor it is essential to cut down the quantity of fluid supply when the motor is idling and to increase the quantity in proportion to the load. This is effected by means of a valve placed with- 70 in the hollow plug K, said valve being forced towards its seat by the pressure of the fluid supply and away from its seat by the back pressure from the rotary motor.

As preferably constructed, a ball valve R 75 is placed within the plug K adjacent to a seat S and is retained in this position by a perforated stop member T. The plug K is of conical form and at the small end of this cone is an adjustable stop pin U which 80 may be set to hold the ball from its seat any amount desired. The plug K is provided with an annular chamber S' adjacent to the seat S and the longitudinal grooves S² which allow the fluid pressure to pass 85 by the ball R when it is withheld from its seat. The pin U has a threaded portion U' engaging corresponding threads in the plug with a polygonal head U² at the outer end and a lock nut U³ for holding it in any 90 position of adjustment. A spring V is sleeved upon the pin U and cooperates with the back pressure from the rotary motor to force the ball away from its seat. The cas- 95 ing W for the valve is preferably formed integral with the casing W' for the rotary motor. The valve K is inserted through one end of this casing and the nipple connection J is attached to this end by a cap or gland X. The spring Y engaging a coun- 100 terbore in the nipple J and bearing against the end of the valve serves to yieldably force the latter against its seat.

In operation, the pin U is adjusted so that the ball valve R will be displaced a 105 sufficient amount from its seat to furnish the air necessary for running the rotary motor without load. The pressure of the fluid supply on the opposite side of the valve R will normally hold the latter against 110

the pin U and against the tension of the spring V. When, however, a load is placed on the rotary motor, which either stops or slows its operation, the back pressure, which will build up and operate against the valve R together with the tension of the spring V, will shift said valve away from its seat, admitting a larger quantity of air to the rotary motor. Thus the valve R will automatically change its position according to load to supply the requisite amount of fluid.

By placing the automatic governing valve within the throttle, a much more compact arrangement is obtained as well as a simplified construction.

What I claim as my invention is:

1. The combination with a percussive and a rotary motor, of a throttle valve for supplying fluid to each of said motors, and an automatic governing valve for the rotary motor within said throttle valve.

2. The combination with a percussive and a rotary motor, of a throttle valve for controlling the fluid supply to each of said motors, a governing valve for the rotary motor within said throttle valve arranged to be forced towards its seat by the pressure of fluid supply and away from its seat by back pressure from the rotary motor, and an adjustable stop for holding said valve from its seat.

3. The combination with a percussive and a rotary motor, of a throttle valve for controlling the fluid supply to each of said motors, said valve being hollow, a ball valve within the hollow of said throttle valve, a seat towards which said ball valve is forced by the pressure of the fluid supply, a stop adjustable to hold said ball valve a varying distance from its seat, and a spring cooperating with the back pressure against said valve for forcing the same away from its seat against the pressure of the supply fluid.

4. The combination with a percussive and a rotary motor, of a throttle valve for controlling the same comprising a hollow conical plug, means for supplying the motive fluid to the chamber within said plug, a ball valve within said chamber, a seat for said valve towards which it is forced by the pressure of the fluid supply, a stop pin arranged axially within said throttle valve and adjustable to hold said ball valve a varying distance from its seat, and a spring sleeved upon said pin bearing against said valve and cooperating with the back pressure from the rotary motor to force said valve from its seat.

5. The combination with a percussive and a rotary motor, of a throttle valve for controlling the same comprising a hollow conical plug, means at the large end of said plug for connecting the fluid supply thereto, ports in said plug cooperating with regis-

tering ports for controlling the supply to the percussive and to the rotary motors, a ball valve in the chamber within said plug, a seat for said ball valve intermediate the ports for the percussive and the rotary motors, a stop pin extending axially into said plug valve from the small end thereof, said pin having a threaded portion rotatively adjustable to force said ball valve from its seat, and a spring sleeved upon said pin and bearing against said ball valve to cooperate with the back pressure from the rotary motor and forcing said ball from its seat.

6. The combination with a percussive and a rotary motor, of a throttle valve for controlling the fluid supply to each of said motors, a governing valve for the rotary motor within said throttle valve, and a stop for holding said governing valve from its seat.

7. The combination with a percussive and a rotary motor, of a throttle valve for controlling the fluid to each of said motors, a governing valve within said throttle valve arranged to be forced towards its seat by the pressure of fluid supply, and a stop for holding said governing valve from its seat.

8. The combination with a percussive and a rotary motor, of a throttle valve for controlling the fluid supply, a governing valve within said throttle valve arranged to be forced towards its seat by the pressure of fluid supply, and an adjustable stop for holding said governing valve a variable distance from its seat.

9. The combination with a plurality of motors, of a throttle valve for supplying fluid to each of said motors, and an automatic governing valve for one of the motors within said throttle valve.

10. The combination with a plurality of motors, of a throttle valve for supplying fluid to each of said motors, and means in said throttle valve responsive to back pressure from one of said motors for varying the supply of fluid to said motor.

11. A valve adapted simultaneously to control the supply of motive fluid to a plurality of motors, said valve having means responsive to back pressure from one of the motors for varying the supply of fluid to that motor, said means permitting passage of a predetermined amount of fluid when said motor is unloaded.

12. A valve adapted simultaneously to control the supply of motive fluid to a plurality of motors, said valve having means in the form of a governing valve arranged automatically to vary the supply of fluid to one motor in response to back pressure therefrom, said governing valve permitting a limited flow of fluid when its motor is unloaded, and means for adjusting said governing valve to increase or decrease the flow

of fluid thereby during the unloaded condition of its motor.

13. A throttle valve adapted for the simultaneous control of a pair of fluid pressure operated motors, and having means differentiating automatically the fluid pressure supply to said motors in response to back pressure from one of said motors.

14. A valve adapted simultaneously to control the supply of motive fluid to a pair of motors, said valve having an automatic governing valve controlling the fluid supply to one of the motors, an adjustable stop arranged to hold said last-named valve off its seat against the thrust of the motive fluid thereby normally to admit fluid in predetermined amount to its motor, said last-named valve operating automatically in response to an increase in back pressure

from its motor to increase the supply of motive fluid thereto.

15. A valve adapted simultaneously to control the supply of motive fluid to a pair of motors, a governing valve therewithin forced toward its seat by the motive fluid, said governing valve controlling the supply of fluid to one motor, an adjustable stop holding said governing valve from its seat to admit fluid in predetermined amount to its motor, said governing valve being responsive to an increase in back pressure from its motor to increase the amount of fluid supplied thereto, and resilient means engaging said governing valve and continuously tending to force the same away from said stop.

In testimony whereof I affix my signature.
WILLIAM A. SMITH.
